WEED DIGGER

Virgil R. Clark, Fullerton, Nebr. 68638

Filed June 6, 1968, Ser. No. 12,237

Term of patent 14 years

Int. Cl. D8—01

U.S. Cl. D8—4

FIG. 1

FIG. 2

FIG. 3

FIG. 4

FIG. 5

FIG. 1 is a perspective view of the weed digger of this invention;

FIG. 2 is a bottom plan view thereof;

FIG. 3 is a front elevational view thereof;

FIG. 4 is a side elevational view thereof, the view from the opposite side being a mirror image thereof; and

FIG. 5 is a rear elevational view thereof.

The design has been shown broken away in FIGS. 3, 4 and 5 for convenience of illustration.

The broken lines are for illustrative purposes only.

I claim:

The ornamental design for a weed digger, substantially as shown and described.
